UNITED STATES PATENT OFFICE.

JACOB SAMUELS, OF NEW YORK, N. Y.

STOCKING.

1,123,014.

Specification of Letters Patent. Patented Dec. 29, 1914.

Application filed June 1, 1914. Serial No. 342,097.

To all whom it may concern:

Be it known that I, JACOB SAMUELS, a citizen of the United States, and a resident of the city of New York, borough of the Bronx, in the county of Bronx and State of New York, have invented a new and Improved Stocking, of which the following is a full, clear, and exact description.

This invention relates to wearing apparel and has particular reference to stockings.

Among the objects of the invention is to provide peculiar attaching tabs or means for the upper end of a stocking which adds to the convenience of the attachment of the stocking supporter, improves the appearance of the stocking and renders it more comfortable than stockings as usually made.

The foregoing and other objects of the invention will hereinafter be more fully described and claimed and illustrated in the drawings forming a part of this specification in which like characters of reference indicate corresponding parts in all the views, and in which—

Figure 1 is a side view of the upper portion of a stocking showing my improvement thereon; Fig. 2 is a perspective view of a slight modification; Fig. 3 is a vertical section on the line 3—3 of Fig. 1; and Figs. 4 and 5 are transverse sections on the lines 4—4 and 5—5 of Fig. 3.

The several parts of the device may be made of any suitable materials; and the relative sizes and proportions, as well as the general design of the mechanism, may be varied to a considerable extent without departing from the spirit of the invention hereinafter more fully set forth and specifically claimed.

At 10 I show the top of a stocking to which may be connected any suitable number or arrangement of my fastening devices. In order to avoid the necessity of securing the stocking supporter directly to the stocking or its hem, thereby avoiding the likelihood of tearing, running or unraveling of the stocking, I provide a tough flexible ear 11 with peculiar reinforcing means therefor in the form of a facing member 12.

The ear 11 consists preferably of a short strip of tape or the like of non-elastic construction secured at its lower end only to the stocking, as shown at 13. The main portion of the ear, therefore, is free from that portion of the stocking against which the ear bears and hence does not interfere

with the elasticity of the upper portion of the stocking.

An eyelet 11' is formed in the upper end of the ear, the same being preferably circular, or the material of the ear is so cut out as to allow free passage outwardly therethrough from between the ear and the stocking 10 of the supporter clasp.

The facing and reinforcing member 12 has a width considerably greater than the width of the ear 11 and is stitched or otherwise secured permanently along its vertical edges at 12' to the stocking and at its lower edge the facing may be stitched, as shown at 12'', or left unstitched as shown in Fig. 2. The term "stitching" as used herein will be understood as being indicative of any suitable fastening means. The upper portion of the ear along the side edges and top edge is secured by stitching or the like, as shown at 11', to the facing 12. The eyelet structure 11' also makes a positive securing means between the rim of the eyelet and the facing. As indicated by Figs. 1 and 2, therefore, the facing lies substantially flat against the upper end of the stocking and presents a neat appearance with no projecting or depending parts which would look unsightly or tend to cause abrasion or friction. The facing 12 is preferably formed of material which, like the stocking, is elastic, and hence this portion of the stocking retains substantially the same elasticity with the facing as it would without it, and since the upper end of the ear is free from the stocking, a wider tape may be used without decreasing materially the circumferential elasticity of the stocking than has heretofore been used when the tape is secured throughout its length to the stocking, and because I may use a wider tape without loss of elasticity, I am enabled to form the eyelet well open as shown, instead of using a mere slit through which the supporter clasp must be forced. The facing being secured to the tape constitutes a reinforcement therefor, making even a narrow tape strong enough while the open eyelet is used.

As indicated in Fig. 2, the facing 12 may be so related to the upper edge of the stocking as to be slightly loose when the stocking is contracted. By this means the stocking may be stretched to a certain extent before the facing begins to stretch. In any event, however, both parts lie substantially

flat and against each other when the stocking is being worn.

Having thus described my invention, I claim as new and desire to secure by Letters Patent:—

1. The combination with a stocking, of an attachment member therefor comprising a strip of tough flexible non-elastic material secured at its lower end only to the stocking, and a facing member covering the non-elastic member and secured to the upper portion thereof and having its lateral edges secured to the stocking.
2. The combination with a stocking, of an attachment member therefor comprising a non-elastic flexible strip secured at its lower end only to the stocking, the upper end of the strip being free from the stocking and having an eyelet therethrough, and a facing member of elastic material secured to the upper end of the strip and around the periphery of the eyelet, said facing member being of considerably greater width than the non-elastic strip and being secured along its lateral edges to the stocking.
3. The combination with a stocking, of an attachment member therefor comprising a comparatively narrow strip of non-elastic material having its upper end free from the stocking and having a circular eyelet formed therethrough, and a facing member

of greater width than the non-elastic strip and secured to the side edges and upper edge of the non-elastic strip, said facing member being formed of elastic material and being secured to the stocking along lines remote from the non-elastic strip, the portion of the facing member adjacent the eyelet being stitched to the strip to form a reinforcement for the eyelet portion thereof.

4. In a device of the character set forth, the combination with a stocking, of an attachment member therefor comprising a tough, flexible, non-elastic strip secured at its lower end to the stocking and extending upwardly and having its upper end free from the stocking and provided with an eyelet, and means extending laterally from the non-elastic member on opposite sides and above the center of the eyelet and securing said member to the stocking along substantially vertical lines remote from the non-elastic member.

In testimony whereof I have signed my name to this specification in the presence of two subscribing witnesses.

JACOB SAMUELS.
